PIPETTE

David J. Cohn, Chicago, Ill.

Application February 12, 1942, Serial No. 430,535

2 Claims. (Cl. 222—478)

The invention relates to pipettes of the type used in chemical or biological laboratory work.

The general object of the invention is to provide a pipette of such inexpensive construction that it may be used once and then thrown away.

Another general object is to provide a pipette of inexpensive construction so that it need not be used more than once, and of such accuracy that it is equivalent to or even better than the present pipettes made of glass.

More specifically, it is an object to provide a pipette comprising a tube of substantially transparent material formed on a mandrel to provide an inner bore of uniform diameter and suitably reinforced at such places, particularly the ends, where the flexibility of the transparent material would be undesirable.

Other objects and advantages will become apparent from the following description, taken in connection with the accompanying drawing, in which:

Figure 1 is a perspective view of a pipette embodying the features of the invention.

Fig. 2 is an enlarged longitudinal sectional view of the pipette shown in Fig. 1.

Fig. 3 is a perspective view of the plug utilized in the upper end of the pipette.

Fig. 4 is a perspective view of the plug used in the lower end of the pipette.

Fig. 5 is a longitudinal sectional view of a modified form of pipette.

Fig. 6 is a perspective view of a plug used in the lower end of the pipette shown in Fig. 5.

Fig. 7 is a longitudinal sectional view of another modified form of pipette.

Fig. 8 is an end view of the lower or tip end of the pipette shown in Fig. 7.

Pipettes employed in chemical and biological work comprise elongated tubes of predetermined capacity and are used for drawing off a measured quantity of liquid from a vessel containing a larger quantity. Heretofore pipettes have usually been made of glass tubing having relatively thick walls. The lower end, or the end adapted to be placed in the vessel containing the liquid, is usually drawn or beveled down to a reduced diameter so that the bore therethrough is substantially less than the internal diameter of the tube itself. The liquid is drawn into the pipette by placing the upper end in the user's mouth and sucking upon it. The upper end of the pipette then is closed by placing the finger thereon and the relatively small diameter of the passage through the lower end prevents any of the liquid from running out of the pipette. The shape of the lower

end also facilitates the formation of drops when the upper end is slightly open to permit air to enter the interior of the pipette.

Great care must be exercised in the manufacture of pipettes in order to produce a relatively uniform inside diameter to permit measurement of the contents by the uniform application of graduated indicia on the outer surface of the pipette. In the case of glass pipettes, because of the inability to obtain exact uniformity between different pipettes, each pipette of high grade must be individually calibrated. Also, with a glass pipette, the meniscus of the liquid, be it concave or convex, is relatively large so that there is chance of error in the measurement of the liquid drawn into the pipette.

Because of the difficulties involved in making an accurate pipette, the expense thereof is relatively high. Thus it is necessary to use such pipettes over and over again with meticulous care exercised in the cleansing of each pipette after use. Such cleansing involves placing each pipette in an acid or alkaline solution with thorough subsequent rinsing and drying. For bacteriological and seriological work the pipette must be thoroughly sterilized and then perhaps carefully wrapped to avoid contamination. Not only is this an expensive procedure from the standpoint of the labor involved, but also from the standpoint of the chemicals used in the acid or alkaline solution. In fact, under present conditions produced by the war, some of these chemicals that have heretofore been commonly used are now almost impossible to obtain.

In using pipettes for certain work, the upper end of each pipette is packed with a cotton filter to prevent passage of bacteria either from the mouth of the user into the liquid in the pipette, or from the liquid into the mouth of the user. Thus before cleansing and sterilizing a glass pipette, the cotton filter has to be withdrawn and before the next use a new filter inserted.

As mentioned above, the principal object of the present invention is to provide a pipette which is so inexpensive to manufacture that it may be used once and then thrown away. Thus many of the disadvantages and difficulties occurring with the use of glass pipettes are obviously avoided. I have found that a thin-walled tube made of inexpensive plastic material which is substantially transparent is suitable. A material of this character which is commonly known by the trade-mark "Cellophane" may be employed for this purpose, and a pipette made thereof may be

as accurate as a glass pipette, or even more so, as well as provide a number of other advantages.

The tube is preferably formed in the manner usually employed in making Cellophane tubes, that is, by wrapping a relatively narrow strip of Cellophane of uniform thickness helically around a mandrel and simultaneously causing the edges of the strip to adhere to each other. The mandrel maintains an unvarying internal diameter and the tension on the strip as it is being wound is maintained constant so that the resultant tubes are extremely uniform throughout their length. Cellophane has the advantages of not being readily attacked by chemicals, of being transparent, and of being materially unaffected by temperatures up to 110° to 120° centigrade, which temperatures are sufficient for sterilization. It is also nonbreakable, light in weight, and as mentioned above, inexpensive. A further advantage has been noted in its use in that many of the liquids encountered in routine hospital work do not form such an accentuated meniscus in a Cellophane tube as in a glass tube, so that an accurate determination of the level of liquid in a Cellophane pipette can be more easily made than in a glass pipette.

In the preferred form of the device shown in Figs. 1 to 4, inclusive, the pipette comprises an elongated tubular body 10 made of Cellophane in the manner above described. Since a thin-walled Cellophane tube of this character is to some extent yieldable, those portions of the tube, particularly the lower end or tip, which are subjected to forces capable of distorting the tube are preferably reenforced. Thus in the lower end of the tube I provide in the preferred form a tip 11 adapted to fit snugly within the tube. To insure a tight fit, advantage is taken of the pliable and resilient character of the plastic material, the diameter of the tip being such that it will be frictionally retained within the tube without the necessity of providing any particular fastening means. In the preferred form the tip 11 has an upper portion within the tube and a slightly larger lower portion 12 providing a shoulder 13 adapted to abut against the end of the tube.

Since it is desired to retain liquid within the pipette merely by sealing the upper end thereof, the tip 11 is provided with a passage 14 which is relatively smaller in diameter than the internal diameter of the tube so that air cannot creep into the tube through the passage 14 when there is liquid therein. The passage 14 should also be formed so that the liquid can be permitted to pass out of the pipette in a smooth stream when desired, or to facilitate the formation of drops when small amounts of air are permitted to enter the top of the pipette. To this end, the passage 14 is of substantial length and the lower end of the plug is externally beveled or partially tapered as at 15. In the preferred form, the bore 14 is preferably centrally located in the tip. The upper end of the tip may be dished as at 16 to facilitate complete drainage. The tip 11 thus reenforces the tube, provides a proper vent therefore and furnishes a solid end to prevent distortion of the tube when pressed against an object.

In the upper end of the tube I also reinforce the tube by providing a top member 20. The top member 20 is preferably frictionally retained within the Cellophane tube, as in the case of the lower tip 11, the lower end of the top member 20 being slightly tapered as at 21 to facilitate insertion, and the upper portion of the top member having a tight fit within the tube. The top mem-

ber 20 preferably has its upper end flush with the upper end of the tube. To permit the passage of air into and out of the tube, the top member 20 is vented as by a central aperture 22. This aperture is substantially smaller than the outside diameter of the top member so that the end face of the member in itself and with the end edge of the Cellophane tube provides a relatively large flat surface against which the finger may be placed to effectively seal the aperture after liquid is drawn into the tube.

The top member 20 is also constructed so that it may carry a cotton filter. Thus the cotton filter may be inserted, during manufacture, directly into the member rather than having to insert it first into the tube. To this end the member is cupped, as at 23, with the cupped portion opening inwardly of the tube. The cotton filter, indicated at 24, may then be packed in the member 20 prior to insertion of the member in the tube.

The members 11 and 20 may be made of any rigid material resistant to acid or alkaline liquids, and capable of being formed either by cutting or molding. Thus the members may be made of molded ceramic material, or preferably are made of plastic molded material such as Lucite.

The exterior of the tube may be marked with suitable graduated indicia 25 similar to those utilized on a glass pipette. However, the indicia may be placed thereon by surface application such as ink or paint sufficient for one-time use, and would not have to be etched into the material as in the case of the glass pipette. Because of the accuracy maintained for the internal diameter of such Cellophane tubes and the uniformity of thickness of the material, the tubes do not have to be individually calibrated and the location of the indicia on one tube of a given size will be exactly the same as on another.

A pipette of this construction may be sterilized and wrapped as a part of its manufacture. Also, the cotton filter 24 may be inserted in the top member 20 as a part thereof. Such pipettes may therefore be supplied to the laboratory ready for use without any doubt as to their sterile condition, or whether there is any foreign residue left in the pipette from its last use or from a cleansing process.

In the modified construction shown in Fig. 5, the Cellophane tube and the indicia thereon are of the same character as in the preferred form. The members in the respective ends thereof, however, are of less expensive construction. Thus each member comprises a piece cut from a cylindrical bar and provided with a longitudinal groove 30 along one side thereof. The groove 30 may be milled into a long rod from which the pieces are cut and is preferably of rounded form, as is apparent from Fig. 6. The grooves 30, together with the adjacent portions of the tube, provide suitable vents at the top and bottom of the tube. The tip member, in order to facilitate proper flow therethrough, may be cut at an angle, as indicated at 31, sloping outwardly toward the side of the member in which the groove 30 is located. Such a construction is obviously very inexpensive since these members may be readily formed from a long rod of the material with only slight machining operations to properly shape them.

In the modified form shown in Fig. 7, the Cellophane tube is also of the same construction as in the preferred form. However, the upper end of the tube is reinforced by a top member of a substantial length so that not only is the

end portion reenforced but the portion therebelow which is usually grasped in handling the pipette is also reenforced. To this end I provide a top member comprising a sleeve 32 of Cellophane, oiled paper, or the like, having an external diameter fitting snugly within the end of the tube. The sleeve 32 extends well down into the tube, say for two or two and one-half inches, and thus makes the tube rigid for the length of the sleeve. The bore of the sleeve is such as to permit the proper flow of air into and out of the tube, while the end edge of the sleeve together with the end edge of the tube, provides a flat area surrounding the bore and facilitates sealing of the bore when the finger is placed thereover. In the lower end of the pipette I may provide a tip 33 comprising a piece cut from a cylindrical rod or bar and having one side thereof cut flat as at 34 to provide a suitable passage between the tip and the Cellophane tube. The lower end of the tip is preferably cut at an angle, as indicated at 35, sloping outwardly toward the flat side 34. The flattened side 34 may be formed either by milling or by mere abrading so that the manufacture thereof is very inexpensive.

While in the three embodiments of the invention I have shown certain forms of tip members with certain forms of top members, it is to be understood that any of the three forms of tip members may be used in a pipette in which any of the three forms of top members is used.

From the foregoing, it will be apparent that I have provided a pipette of such inexpensive construction that it may be thrown away after having once been used. It is fully as accurate as glass pipettes now available because of the inherent accuracy resulting from the manufacture

of the tube. While the tube has a relatively thin wall and consequently is in itself yieldable, it is reenforced at such points, particularly the ends, where any pressure is exerted upon it. By its suitability for one time use, it eliminates all the difficulties involved in cleansing and sterilizing, both from the standpoint of the labor and the difficulty of obtaining cleansing materials.

I claim as my invention:

- 10 1. A pipette comprising a tube made of a thin flexible strip of a cellulose plastic material helically wrapped to a uniform diameter, and members in the respective ends of said tube to reinforce the tube at the ends, the member at the lower end being provided with an elongated passage of substantially smaller diameter than the internal diameter of the tube for regulating the flow from the tube, and the member at the upper end being vented to permit passage of air into or out of the tube and having an end surface cooperating with the end surface of the tube to provide a relatively flat area surrounding the vent, whereby the vent may be readily sealed by placing the finger thereover.
- 15 2. A pipette consisting of a tube composed of a thin flexible strip of a cellulose plastic material helically wrapped to a uniform internal diameter, and a tip member having a cylindrical portion in tightly fitting relation to the lower
- 20 30 end of the tube and providing an elongated passage of a diameter substantially smaller than the internal diameter of the tube for the discharge of fluid from the tube, the upper end of the tube being constructed so as to be sealed by placing the finger thereover, and a calibrated scale printed directly on the tube.

DAVID J. COHN.
